INVENTOR.
Henry O'Neill
BY *George W. Dill*
ATTORNEY

UNITED STATES PATENT OFFICE.

HARRY O'NEILL, OF CHICO, CALIFORNIA.

FLOAT-CONTROLLED FLUSH VALVE.

Application filed March 27, 1922. Serial No. 546,987.

To all whom it may concern:

Be it known that I, HARRY O'NEILL, a citizen of the United States, residing at Chico, county of Butte, State of California, have invented certain new and useful Improvements in Float-Controlled Flush Valves; and I do declare the following to be a full, clear, and exact description of the same, reference being had to the accompanying drawings, and to the characters of reference marked thereon, which form a part of this application.

This invention relates to improvements in flush valves such as are used in connection with toilet flush-tanks, the main objects of my invention being to provide a flush-valve structure in which the common rubber float-ball with its trouble-giving propensities as to leakage and rot is eliminated; there is only a single valve-seat or gasket member which any one can replace in a few seconds if necessary but which should wear for several years; there is but very little wear possible, since the parts are substantial and the number and complication thereof is reduced to a minimum; and the flush when in operation is practically noiseless, the last being by no means the least of the advantages of my device.

My device, except for the individual type of trip-handle used, is equally adaptable for high and low tanks, and whether these are of old or new styles.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Fig. 1 is a sectional elevation of a tank, showing my improved valve and flush structure therein, also partly in section.

Fig. 2 is an enlarged detached view of the valve member, just after the trip has been actuated.

Fig. 3 is a similar view, showing the relation of the parts when the tank is emptied.

Fig. 4 is a view of a type of handle member for use with low-set tanks, taken on the line 4—4 of Fig. 1.

Fig. 5 is a view of a trip actuating means for use with high tanks.

Fig. 6 is an enlarged section of a nozzle.

Referring now more particularly to the characters of reference on the drawings, the numeral 1 denotes a tank having a water intake pipe 2, and a larger pipe 3 leading to a toilet bowl, this latter pipe having a goose-neck or bend 4 a short distance above the full water-level line A, and a downward continuation 5 of said bend open on the bottom and terminating a short distance from the bottom of the tank.

Extending horizontally in the tank is a bracket 6, on the outer end of which is fitted an inverted L shaped and hollow connection 7 the outer horizontal end of which is suitably connected as by means of a union and elbow 8 to the upper end of the supply pipe 2 while the lower end is similarly connected to a pipe 9 the lower end of which is bent to project up into the pipe 5 a short distance and preferably has a nozzle 10 on that end. The pipe 9 however may be formed integral with the fixture 7 if desired.

Seated between the union 8 and the fitting 7 and firmly held in place is a tubular member 11, projecting into said fitting, the opening through which is adapted to be closed by a valve member 12 slidably mounted in the fitting 7 and projecting therethrough at the end thereof adjacent the bracket. This valve has on its end facing the member 11 a gasket 13 preferably of pure rubber, and which is seated in said valve so as to be readily replaced when necessary. Extending in alignment with the valve 12 and therebeyond, and slidable in a groove 14 formed in the bracket 6 is a trip-pin or valve releasing and holding member 15, the end of which opposite to the valve 12 is pivoted onto an arm 16 which in turn is pivoted below the connection of the pin 15, the upper end of said arm having a rod 17 extending therefrom substantially at right angles thereto and carrying on its outer end a ball-float 18 of the usual type.

The pin or rod 15 has a lug 19 projecting up from adjacent its free end, to which is flexibly connected one end of a link 20 the upper end of which is similarly connected (if used with a low-set tank) to the end of a crank arm 21 formed on a turnable rod 22 mounted in the front side of

the tank and having an operating handle 23 on its outer end, as shown in Fig. 4.

For a high tank, the pin-controlling link 20^a is supported at its upper end by a slotted yoke 24 fixed on one end of a horizontally disposed lever 25 which extends over the top of the tank 1^a for a certain distance, and is pivoted thereon by a bracket 26. The outer end of the lever is connected to a pull cord or chain 27 which extends down to within reach of the operator.

The nozzle 10 is formed as a tubular member 10^a secured in the pipe 9 from the upper face of which a number of holes 10^b are drilled down at an angle to communicate with the interior of said member.

A tubular member 10^c is adjustably screwed into the member 10^a, so that the size of the hole openings may be regulated 20 as desired, thereby adjusting the force of the flow.

In operation, suppose the tank to be full, as shown in Fig. 1, in which it will be noted that the float 18 is raised, causing 25 the pin 15 to move along its guide in the bracket, engaging the valve 12 and forcing the latter into contact with the member 11, thereby closing the opening therethrough and stopping the admission of water from 30 the pipe 2 to the pipe 9. If the float is properly adjusted, this closure of the valve will take place when the water level is just below the bend 4 of the flush pipe 3.

Now if it is desired to flush the toilet, the 35 link 20 or 20^a is raised by manipulation of the handle 23 or lever 25 respectively. This will cause the pin 15 to be raised at its end adjacent the valve 12 to a point above the latter sufficient to permit the water pressure 40 constantly in the pipe 2 to force the valve 12 away from its seat member 11 and thus allowing the water in the pipe 2 free access to the pipe 9, as shown in Fig. 2.

The water level in the pipe extension 5 45 is then raised until it overflows through the bend 4 into the pipe 2 when a siphoning action is at once set up, the start of this action being speeded up by reason of the intake pipe 9 discharging directly into the pipe 5, causing the tank to be rapidly drained and the float 18 to be lowered, until the water is at the lower end of the pipe extension 5, which allows air to enter the same and terminates the siphoning action 55 while leaving plenty of water in the toilet bowl for a seal.

Owing to the fact that the extension 5 60 is very nearly full before the tripping or flushing action is started, so that the operation is practically noiseless, and the objectionable roar had with the ordinary flush

tank is practically eliminated. It will also be noted that the need and use of a rubber-ball to close the outlet is done away with, so that if the gasket 13 makes a good seal 65 with the seat 11 no leakage of water is possible.

Now when the float 18 is lowered with the lowering of the water the pin 15 gradually moves to the rear of the valve 12 and finally drops behind the same onto its grooved seat 14 and in alignment with the valve (see Fig. 3) in position to once more engage and force the same toward its seat 11 as the water level is gradually raised by 75 the incoming water.

The nozzle with its plurality of outlets sends the water forcibly up into the member 5, resulting in a quicker siphoning action than would otherwise be had. 80

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended 85 claims.

Having thus described my invention, what I claim as new and useful and desire to secure by Letters Patent, is:—

1. A flush system for toilet tanks and the like comprising a water intake pipe passing into the tank, an outlet pipe therefrom, a valve member for closing the intake pipe, slidably mounted with respect thereto and projecting outside the same, an independent pin in normal alignment with the valve member and adapted to engage the outer end thereof, float controlled means for moving the pin toward the valve as the tank is filling and to which the opposite end of the pin is pivoted, and hand actuated means for raising the end of the pin nearest the valve out of engagement with the latter whereby the valve is free to move outwardly of the intake pipe, the water pressure in said pipe acting to force it in that direction. 100

2. In a flush system for tanks, an intake pipe extending into the tank, an outlet pipe leading therefrom and terminating in the tank in a downwardly directed and open end, a nozzle on the intake pipe projecting up into the open end of said outlet bend, said nozzle having a plurality of upwardly directed orifices, and means for altering the sizes of all said orifices in common. 115

In testimony whereof I affix my signature.
HARRY O'NEILL.
